UNITED STATES PATENT OFFICE.

WILLIAM H. SLOAN, OF WINSTON-SALEM, NORTH CAROLINA.

CHIMNEY-HOLDING ATTACHMENT FOR LAMPS.

1,216,864.

Specification of Letters Patent. Patented Feb. 20, 1917.

Application filed November 24, 1916. Serial No. 133,142.

To all whom it may concern:

Be it known that I, WILLIAM H. SLOAN, a citizen of the United States, and a resident of Winston-Salem, in the county of Forsyth and State of North Carolina, have invented a certain new and useful Improvement in Chimney-Holding Attachments for Lamps, of which the following is a specification.

My invention relates generally to lamps, and more particularly to oil lamps, the object thereof being to provide means whereby lamp chimneys may be readily, quickly, and positively clamped in position in connection with the lamp burner, and of such nature as that they may be quickly and easily released to permit of removal of the chimney for purposes of cleaning, repair, and substitution, and when the lamp is lighted.

Further objects, together with the advantages of my invention, will appear in the course of the following description thereof, reference being made to the accompanying drawing forming a part of this specification, and wherein—

Figure 1 is a perspective view illustrating the practical application and use of the invention;

Fig. 2 is a plan view of the lamp burner;

Fig. 3 is a detail perspective view of the annular shifting ring removed;

Fig. 4 is a detail perspective view of the lamp burner with the shifting ring removed;

Fig. 5 is a detail perspective view of the controlling spring.

Referring now to these figures, my invention is utilized in connection with an oil lamp of the general type shown in Fig. 1, wherein the burner is utilized in connection with an oil burning receptacle 15, and includes a horizontally disposed body plate 16, the inner portion of which is perforated as usual and provided with a central wick holding member 18, the wick adjusting means being generally seen at 19, and the

outer portion 20 of which is in the nature of an annular substantially flat rim having radial slots 21 in its outer peripheral edge and at spaced points therearound, forming guides for the vertically projecting chimney-clasping arms 22 which work in the slots 21 for engagement with and disengagement from the lamp chimney 23, under the control of operating means to be now described.

The arms 22 are preferably formed of flat metal so as to cast minimum shadow,

and have their upper ends 23 twisted and bent to form engaging heads, the lower extremities of the arms 22, below the body plate 16, being pivotally connected to the lower ends of brackets 24 secured to and depending from the body plate 16 of the burner, as best seen in Figs. 1 and 4, so that the upper portions of the arms 22, including their clasping heads, are movable radially, inwardly toward, and outwardly away from, the burner cap 25.

Mounted in flatwise sliding relation upon the burner rim 20 of the body plate 16, is an annular adjusting ring 26, of somewhat greater diameter than the diameter of the said rim 20, and provided around its inner peripheral edge with a plurality of integral bent lugs 27 which slidably engage the lower surface of the rim 20 so as to maintain the adjusting ring 26 thereon, against accidental displacement. The ring 26, as shown particularly in Fig. 3, is further provided at spaced points therearound, with curved slots 28, each disposed eccentrically with respect to the axis of the plate, and each receiving one of the vertically projecting clasping arms 22 therethrough, as clearly seen in Figs. 1 and 2, the ring 26 having a depending integral finger-piece 29 bent angularly from its outer peripheral edge portion, and provided with a slot 30.

The finger-piece 29 of the ring 26 opposes, in spaced relation, a similar finger-piece 31, secured to and depending from the under surface of the rim 20 of the body plate, and having a slot 32, the slots 30 and 32 of the two finger-pieces receiving the angularly bent outer ends 33 of a U-shaped spring member, projecting inwardly beneath the body plate 16, so as to normally maintain the finger-pieces 29 and 31 in spaced apart relation so as to hold the chimney-clasping arms 22 at the inner ends of the curved slots 28.

When the operator, however, grasps the two finger-pieces 29 and 31 and moves the former toward and against the latter, against the tension of spring 34, the adjusting ring 26 is partly rotated upon the rim 20 of the body plate, so that the outer side walls of the slots 28, acting as cams against the outer edges of the clasping arms 22, will shift the latter in their guide slots 21 of the rim 20, forcing the latter outwardly away from the burner cap 25, and consequently out of clasping engagement with the

chimney 23, to permit ready removal of the latter, for purposes of cleaning, repair, or substitution, and when the burner is to be lighted, the reverse of this movement being true when the finger-pieces 29 and 31 are released by the operator, allowing the latter to move apart under tension of the spring 34.

To permit of more effective engagement of the clasping arms 22, the chimney 23 as shown in Fig. 1, is provided with an annular groove or indented portion 35 above its lower edge, into which the upper head 23 of the clasping arms extend in the engaged position, although this particular construction of the chimney is susceptible of change.

It is obvious from the foregoing that my invention provides for effective clasping engagement of a lamp chimney, in such manner as to hold the same firmly and uniformly in position, obviating danger of breakage in use, and yet in such manner as to permit of ready removal of the chimney when desired.

It is further obvious that I provide simple and comparatively inexpensive means whereby the movement of the vertically extending arms utilized for the purpose of clasping the chimney, may be simultaneously controlled in a convenient, quick, and ready manner.

I claim:

1. In a device of the character described, the combination with a lamp burner having a flat annular rim provided with radial slots 25 in its outer peripheral portion, at spaced points therearound, of brackets depending from the under surface of the said rim, chimney clasping arms pivoted at their lower ends to the said brackets and upstanding through the said radial slots, an adjusting ring rotatable upon the rim of the burner, having curved eccentric slots at spaced points therearound, through which the clasping arms extend, said adjusting 40 ring having a depending finger piece, a finger piece secured to and depending from the burner rim and opposing the finger-piece of the adjusting ring, and a U-shaped spring 45 projecting inwardly below the rim of the burner and engaging the said finger-pieces to normally prevent rotary movement of the adjusting ring.

2. In a device of the character described, the combination with a lamp burner having a flat annular rim provided with radial slots 55 in its outer peripheral portion at spaced points therearound, of brackets depending from the under surface of the said rim, chimney clasping arms pivoted at their lower ends to the said brackets and upstanding through the said radial slots, an adjusting ring rotatable upon the rim of the burner, having curved eccentric slots 60 at spaced points therearound through which the clasping arms extend, said adjusting

ring having a depending finger-piece, a finger piece secured to and depending from the burner rim and opposing the finger-piece of the adjusting ring, a U-shaped spring 70 projecting inwardly below the rim of the burner and engaging the said finger-pieces to normally prevent rotary movement of the adjusting ring, said adjusting ring having its inner peripheral edge provided with depending bent lugs extending along the 75 lower surface of the burner rim to prevent vertical displacement of the said adjusting ring.

3. In a device of the character described, the combination with a lamp burner having a projecting rim provided with radial guide slots, of chimney-clasping arms projecting vertically through the said guide slots and pivoted at their lower ends to the burner beneath the rim, an annularly shiftable adjusting ring disposed and movable on the burner rim and provided with curved eccentric slots through which the said clasping arms also extend, said adjusting ring and said burner rim having opposing finger-pieces by means of which the former may be shifted with respect to the latter, and a spring engaging the said finger-pieces to normally hold the adjusting ring against shifting movement.

4. In a device of the character described, the combination with a lamp burner having a projecting rim provided with radial guide slots, of chimney clasping arms projecting vertically through the said guide slots and pivoted at their lower ends to the burner beneath the rim, an annularly shiftable adjusting ring disposed and movable on the burner rim and provided with curved eccentric slots through which the said clasping arms also extend, said adjusting ring and said burner rim having opposing finger-pieces by means of which the former may be shifted with respect to the latter, and a spring engaging the finger-pieces to normally hold the adjusting ring against shifting movement, said adjusting ring having means engaging the burner rim to hold the same thereon, against vertical displacement.

5. In a device of the character described, the combination with a lamp burner having a projecting rim provided with radial guide slots, of chimney engaging arms extending vertically through the guide slots and pivoted at their lower ends to the burner, and means for simultaneously shifting the upper portions of the clasping arms radially toward and away from the center of the burner, said means including an annularly shiftable ring disposed and movable on the 125 burner rim and provided with curved eccentric slots through which the clasping arms also extend.

6. In a device of the character described, the combination with a lamp burner having

a projecting rim provided with radial guide slots, of chimney engaging arms extending vertically through the guide slots and pivoted at their lower ends to the burner, and
5 means for simultaneously shifting the upper portions of the clasping arms radially toward and away from the center of the burner, said means including an annularly shiftable ring disposed and movable on the
10 burner rim and provided with curved eccentric slots through which the clasping arms also extend, and a spring engaging portions of the said adjusting ring and the burner rim, to normally hold the former in inactive position.
15

7. In a device of the character described, the combination with a lamp burner having a projecting rim provided with radial guide slots, of chimney engaging arms extending vertically through the guide slots and pivoted at their lower ends to the burner,
20

means for simultaneously shifting the upper portions of the clasping arms radially toward and away from the center of the burner, said means including an annularly shiftable ring disposed and movable on the burner rim and provided with curved eccentric slots through which the clasping arms also extend, and a spring engaging portions of the said adjusting ring and the burner rim to normally hold the former in inactive position, said clasping arms including upright strips presented edgewise for the major portion of their length toward the center of the burner, and having their upper ends twisted and bent to form chimney-engaging heads presented flatwise toward the center of the burner.
